United States Patent Office

Des. 193,705
Patented Oct. 2, 1962

193,705

VEHICLE CAB

E. A. Domes, Chicago, Ill., assignor to International
Harvester Company, Chicago, Ill., a corporation of
New Jersey

Filed Feb. 27, 1961, Ser. No. 64,070

Term of patent 14 years

(Cl. D14—3)

FIG. 1 is a front elevational view of a vehicle cab, showing my new design;

FIG. 2 is a side perspective view;

FIG. 3 is a side elevational view of the left-hand side of the cab;

FIG. 4 is a side elevational view of the right-hand side of the cab.

FIG. 5 is a plan view of the cab; and

FIG. 6 is a rear elevational view of the cab.

I claim:

The ornamental design for a vehicle cab, substantially as shown.
